Inventor
Edward M. Bentley

UNITED STATES PATENT OFFICE.

EDWARD M. BENTLEY, OF LAWRENCE, NEW YORK.

PERCUSSION TOOL.

Application filed March 3, 1920. Serial No. 363,072.

To all whom it may concern:

Be it known that I, EDWARD M. BENTLEY, a citizen of the United States, residing at Lawrence, county of Nassau, and State of New York, have invented certain new and useful Improvements in Percussion Tools, the following being a full, clear, and exact disclosure of the one form of my invention which I at present deem preferable.

10 For a detailed description of the present form of my invention, reference may be had to the following specification and to the accompanying drawing, which illustrates my invention, wherein—

15 Fig. 1 shows an axial section of my device,

Fig. 2 a transverse section on the line 1—1,
Figs. 3, 4 and 5 show details and

Fig. 6 shows a modification.

20 My tool is of the type wherein a spring is periodically tensioned and released to operate the impact member of the tool.

Referring to the drawing, M represents an electric motor and D a worm driven thereby through a detachable connection. The worm has ball bearings at E and a thrust bearing at F and drives two worm wheels G and H carried by shafts V, mounted in strut bars K, K projecting forward 30 from a diaphragm L. A spring N is contained between a base K¹ on struts K, K and a flange K² on the impact member S. Each worm wheel has a concentric slot d formed in it as shown in Fig. 5 in which fits a pin R projecting from a crank disc A carried by the shaft V. On the opposite side of each disc A is a wrist-pin W from which a connecting rod P leads to one side of the flange K² where it is pivoted to one 40 of the ears k, k.

Assuming the worm wheels to be kept in rotation by the motor, the pins R, R will be periodically caught by the rear ends of the respective curved slots d and rotated 45 approximately 180 degrees, thereby drawing up connecting rods P, P and compressing spring N. When pins R, R reach the dead-center point the reaction of the springs, now relieved of their tension, cause the pins 50 to travel toward the forward ends of the slots d, causing discs A, A, to run ahead of the worm wheels and allow the springs to throw the member S against the tool O. Care should be exercised that the impact 55 of the hammer is taken up by the tool, or,

in the absence of the tool, by the casing, instead of by the connecting rods P, P. Those rods are slotted to allow them to over-run the member S, by virtue of the longer stroke of the crank when the member is arrested by its impact on the tool. After each impact the pins R, R are again picked up by the worm wheels and the described action is repeated. It will be observed that the cranks actuate the 60 spring in the tensioning direction only, but exert no driving effect thereon in the other direction since at that time the force of the gear wheels on the crank is released. The one-way drive of the crank 65 by the gear wheel may be secured by spring pawls T, T on the wheel engaging a ratchet on the periphery of disc A, which in that case is contained in a circular recess in the gear wheel. By this means the gear wheel 70 more quickly picks up the crank disc after the latter has run ahead of the former.

What I claim as new and desire to secure by Letters Patent is:

1. A percussion tool comprising an impact member, an operating spring therefor, a drive gear, tensioning means including rotatable members operatively connected with the spring, and means periodically coupling the drive gear and the tensioning means together, whereby the spring is tensioned and released. 80

2. A percussion tool comprising an impact member, an operating spring therefor, a drive gear, means for continuously operating said drive gear in one direction, a crank disk operatively connected with said spring, and means periodically coupling the drive gear and crank disk together, whereby the spring is tensioned and released. 90

3. A percussion tool comprising an impact member, an operating spring therefor, a drive gear, tensioning means consisting of rotatable means and links connecting said means and said spring, and means periodically coupling the drive gear and said tensioning means together, whereby the spring is tensioned and released. 100

4. A percussion tool comprising an impact member, an operating spring therefor, a drive gear, tensioning means consisting of rotatable means and links connecting said means and said spring, and means periodically coupling the drive gear and said tensioning means together, whereby the spring 110

is tensioned and released, said links being slotted to provide a limited amount of lost motion.

5. A percussion tool comprising an impact member, an operating spring therefor, a drive gear, a crank having a loose connection with said spring, and means periodically connecting and disconnecting said drive gear and said crank.

10. 6. A percussion tool comprising an impact member, an operating spring therefor, a motor, a crank having a loose connection with said spring, and means periodically connecting and disconnecting said motor and said crank.

20. 7. A percussion tool comprising in combination an impact member, an operating spring therefor, a rotatable drive shaft, a speed reducing gear driven thereby, and a rotary connecting device between said spring and said gear and movable independently of the gear, said connecting device and said gear having complementary means adapted to release the connecting device on reaching 25 dead center.

30. 8. A percussion tool comprising in combination an impact member, an operating spring therefor, a rotatable drive shaft, a speed reducing gear driven thereby, a rotary connecting device between said spring and said gear and movable independently of the gear, said connecting device and said gear having complementary means adapted to release the connecting device on reaching 35 dead center, and means whereby said connecting device and gear are caused to reconnect at the end of the impact stroke.

40. 9. A percussion tool comprising an impact member, an operating spring therefor, a motor, a crank, a connecting rod engaging said crank and having a loose connection with said spring, and means periodically connecting and disconnecting said motor and said crank.

45. 10. A percussion tool comprising an impact member, an operating spring therefor, a crank connected with the spring, a gear, and a driving connection between the crank and the gear operative in the direction for tensioning the spring.

50. 11. A percussion tool comprising an impact member, an operating spring therefor, a slotted drive gear, and a crank connecting with the spring and having a pin engaging with the slot of said drive gear.

55. 12. A percussion tool comprising an impact member, an operating spring therefor, a crank, a drive gear, means providing a lost motion connection between the crank and the drive gear, and means providing a lost motion connection between the crank and the spring.

60. 13. A percussion tool comprising an impact member, an operating spring therefor, a crank disk, a drive gear, means providing

a lost motion connection between the crank disk and the drive gear, and a slotted connecting rod between the crank disk and the spring.

65. 14. A percussion tool comprising an impact member, an operating spring therefor, a pair of cranks operatively connected to said spring for tensioning the same, and means periodically actuating the cranks to apply tension to the spring.

70. 15. A percussion tool comprising an impact member, an operating spring therefor, a pair of cranks on opposite sides of said spring, a motor, operating connections between the motor and the cranks, and connections between the cranks and the spring.

75. 16. A percussion tool comprising an impact member, an operating spring therefor, a tensioning member, means connecting the tensioning member and spring, and a worm gear operatively connected with said tensioning means.

80. 17. A percussion tool comprising an impact member, a spring therefor, a motor, a pair of worm gears on opposite sides of the motor shaft and driven thereby, a pair of operating members between each of the respective gears and the spring, and means whereby said operating members are periodically actuated.

85. 18. A percussion tool comprising an impact member, an operating spring therefor, a worm gear, means connected with the spring and periodically engaged with the worm gear for tensioning said spring, a motor for actuating said worm gear, and a detachable connection between the motor and the worm gear.

90. 19. A percussion tool comprising an impact member, an operating spring therefor, a motor, a crank shaft driven by the motor, a drive gear on said shaft having a one-way slip connection with said crank shaft, and means providing a loose connection between the spring and said crank shaft.

95. 20. A percussion tool comprising an impact member, an operating spring therefor, a rotatable member, a motor driving said rotatable member, a rotatable crank member having a one-way connection with the first mentioned rotatable member, and means providing a reciprocating connection between said crank member and said spring.

100. 21. A percussion tool comprising an impact member, an operating spring therefor, a worm gear, a motor driving said worm gear, a crank having a one-way connection with said worm gear, and an operating connection between said crank and the spring for periodically tensioning the latter.

105. 22. A percussion tool comprising an impact member, a spring therefor, a gear wheel, an electric motor driving said gear wheel, a crank member enclosed by said

gear wheel, a one-way connection device between said crank member and the enclosing gear wheel and a reciprocating device connecting said crank shaft and the spring for 10
5 periodically tensioning it.

23. A percussion tool comprising an impact member, an operating spring therefor, a motor, a screw driven by the motor and

operatively connected with the spring for tensioning the same and a dead-centered device for periodically connecting said screw and the spring.

Signed at New York city, county and State of New York, this 5th day of February, 1920.

EDWARD M. BENTLEY.
